UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

SHEET-FEEDING APPARATUS.

1,086,351.

Specification of Letters Patent. Patented Feb. 10, 1914.

Application filed January 31, 1913. Serial No. 745,326.

To all whom it may concern:

Be it known that I, ALBERT B. DICK, a citizen of the United States, residing at Lake Forest, in the county of Lake and State of Illinois, have invented certain new and useful Improvements in Sheet-Feeding Apparatus, of which the following is a specification.

This invention relates to sheet-feeding apparatus and particularly to apparatus of this character adapted for use in connection with stencil duplicating machines.

The invention is directed to the provision of certain improvements in the construction of mechanism for automatically feeding sheets successively from a pile, whereby the mechanism is made more reliable in its operation, that is, whereby the feeding of one sheet and no more at each operation is insured.

The improvements constituting the present invention are of special utility in connection with apparatus for stencil duplicating and sheet-feeding, such as that shown in Patents Nos. 1,054,399 and 1,054,637 granted to me February 25, 1913.

The present invention involves the employment of sheet-feeding apparatus including a rotatable sheet-feeding roller and a rocking feed-board mounted with one end under the feed roller, so that the pile of sheets on the feed-board may be carried by the rocking movement of the board into contact with the under side of the sheet-feeding roller. The roller is adapted to buckle one end of the sheet and then feed that end over the roller to the printing mechanism. The means for rocking the feed-board is such that the board completes one rocking movement during each operation of the printing mechanism and the pile of sheets is allowed to contact with the sheet-feeding roller during a certain portion of this time. I have found that the reliability of the operation of such a machine depends largely upon the length of time which the pile of sheets is allowed to remain in contact with the sheet-feeding roller during each feeding and printing operation and that the proper length of time varies with different qualities of paper. I have therefore provided means whereby the period of contact of the paper with the sheet-feeding roller during each complete cycle of operations of the feeding

and printing mechanism may be regulated as may be made necessary by the quality of the paper being operated upon.

I have illustrated the preferred embodiment of my invention in the accompanying drawings, in which—

Figure 1 is a central section of the machine; Fig. 2 is a horizontal section of a portion thereof; Fig. 3 is a sectional detail view on line 3—3 of Fig. 2 and Fig. 4 is a sectional detail view on line 4—4 of Fig. 3.

Referring to these drawings, the machine consists of a base 1 on which side-frames 2 are erected and a drum 3 mounted for rotation in suitable bearings provided in the side-frames 2. The drum is adapted to have a stencil 4 secured about the cylindrical surface thereof in the usual manner. The drum is rotated by means of a crank 5 secured to a pinion 6 which meshes with a gear 7 fastened to one head of the drum. The pressure-roller is shown at 8, this being carried on pivoted arms 9 in the usual manner and drawn toward the drum by springs 10.

Mounted for rotation in suitable bearings in the side-frames is a shaft 11 on which a sleeve 12 is loosely mounted and this sleeve carries sheet-forwarding sectors 13. These sectors are adapted to coact with a sectional-roller 14 in forwarding sheets between them to the line of contact of the drum and pressure-roller. The sectors 13 are rotated intermittently at the same surface speed as that of the drum and they make one revolution during each revolution of the drum. To effect this the shaft 11 has a gear 15 secured thereto, which is connected by a train of gears 16 to the pinion 6. The gear 15 is secured to a gear 17 meshing with a gear 18 on a shaft 19 and the gear 18 is connected to a mutilated gear 20 also rotatable on shaft 19. This mutilated gear is adapted to mesh with a pinion 21 which is fastened to the sleeve 12 carrying the sectors 13. The sheet-feeding apparatus is adapted to feed sheets successively to the sheet-forwarding devices consisting of the sectors 13 and roller 14 once during each rotation of the drum 3; and the sheet-forwarding devices are adapted to be actuated once during each revolution of the drum to forward a sheet so fed to the drum and pressure-roller.

The pile of sheets 22 is placed upon a feed-

board 23 mounted upon a rod 24 extending between the side-frames 2 and adapted to rock upon that rod. This rocking movement of the feed-board carries the top sheet 5 of the pile into and out of contact with a sheet-feeding roller 25 whose shaft is mounted for rotation in bearings in the side-frames. The shaft of this roller has a pinion 26 secured thereon which meshes with a gear 27 and the latter meshes with the gear 15. By means of this gearing the roller 25 is rotated continuously when the drum is rotated. The feed-board 22 is rocked by means of a lever 28 which carries a roller 30 adapted to ride on the surface of a two-part cam 31 mounted on shaft 11. This lever 28 actuates in a manner hereinafter described an arm 32 carrying a pin which is received in a slot formed in a piece 33 secured to the 20 bottom of the feed-board 23. The roller 30 is held in contact with the cam 31 by means of a spring 34, one end of which is connected to an extension of the lever 28 and the other end of which is connected to an adjustable arm 35.

Figs. 3 and 4 show in detail the construction of the two-part cam 31 and the means for effecting a relative adjustment of the parts thereof. From these figures, it will be seen that the gears 15 and 17 are secured to the hub of a member 36 which is pinned to the shaft 11 and which has one part 37 of the cam secured thereon. The other part 38 of the cam is arranged between the part 37 and a flange 39 on the member 36. This part 38 is rotatable relatively to the part 37. The end of shaft 11 is not located directly in a bearing in side-frame 2, but is mounted in a sleeve 40 which is located in a bearing 40 in side-frame 2. This sleeve has a pin 41 mounted thereon which projects through arc-shaped openings in the gears 15 and 17 and a round opening in the part 38 of the cam. The end of this pin 41 is adapted to enter any one of a plurality of openings 42, (Fig. 3) formed in the periphery of the flange 39 of member 36. The sleeve 40 has an operating handle 43 secured thereon and lying outside the side-frame 2. The flange 50 of this handle 43 may co-operate with a pointer or index 44 secured to the side-frame 2. The shape of the two-parts 37 and 38 of the cam is shown in Fig. 3 from which it is apparent that the raised portions thereof overlap and can be made to overlap more or less by moving one relatively to the other. To effect this movement, the handle 43 is grasped and pulled so as to move sleeve 40 and pin 41 outwardly axially to withdraw the end of pin 41 from the notch 42 in which it lies. This movement is checked at the proper point by the contact of the enlargement of sleeve 40 with the side-frame 2. Then by turning handle 43 the part 38 of the cam will be turned relatively to the part

37, the pin 41 moving in the slots in gears 15 and 17. When the proper position has been found, handle 43 is pushed inwardly so that pin 41 will enter another of the notches 42 thus locking the movable part of the cam in the position to which it has been moved. By adjusting the cam in this way an adjustment is effected of the time during which the top of the sheet pile 22 remains in contact with the under surface of the feeder 25. Adjacent to the feeder 25 is a stop 45 overlying the forward end of the sheet pile and adapted to engage the top sheet thereof. This stop is reciprocated vertically by a bell crank lever 46 pivotally connected at one end to the stop 45 and carrying a roller at the opposite end adapted to contact with a cam 47 mounted on the shaft 11. The cam 47 is so shaped that when the pile of sheets is first moved upwardly into contact with the feeder, the stop will be raised out of contact with the pile so as to allow the end of the top sheet of the pile to be drawn by the feeder from under the stop; immediately thereafter the stop is lowered into contact with the pile to engage the end of the second sheet and prevent this from being drawn off by the feeder while the latter is withdrawing the top sheet; then the stop and the adjacent end of the feed-board are lowered together to carry the paper out of contact with the feeder; and then the downward movement of the stop is discontinued while the downward movement of the adjacent end of the feed-board continues so that the pile 100 of paper is carried out of engagement with the stop to allow a partially buckled second sheet to flatten upon the pile. The buckling of the top sheet takes place between the feeder 25, which is rotated in the direction 105 of the arrow on Fig. 1, and a rod 48 carried by pivoted arms 49. These arms 49 are situated by the machine so that the rod 48 is lowered upon the surface of the pile when the pile is raised into contact with the feeder. After the sheet has been so buckled, its end is engaged by the serrations in the feeder 25 and carried over the feeder whereupon a co-acting roller 50 is lowered into contact with the sheet and the continued rotation of the 115 feeder causes the sheet to be moved along into coaction with the forwarding devices above described.

I have found that a machine of the character above described is far more reliable 120 in its operation if the period of contact of the pile of paper with the feeder 25 during each operation of the machine is of the proper duration and that this period should be more or less depending upon the quality 125 of the paper operated upon. If the period of contact of the paper with the feeder be too long, more than one sheet will probably be buckled and withdrawn from the pile, whereas if that period be too short, no sheet 130

at all will be buckled and withdrawn in many instances. I have therefore provided the adjustable two-part cam whereby the rocking movement of the feed-board during each rotation of the drum may be regulated as desired, so as to effect an adjustment of the period of time in each operation of the machine during which the pile remains in contact with the feeder. As a result of this provision, an adjustment may be made whereby the operation of the machine is made far more reliable.

It would be undesirable to have the limits of the rocking movement of the feedboard the same at all times. If this were done, a rocking movement sufficient to disengage the pile from the feeder when the pile was quite high would cause an unnecessarily large separation of the feeder and pile and useless movement of the parts when the pile was quite low. The mechanism is therefore so arranged that the board is moved so as to separate the pile and feeder substantially the same amount at all times regardless of the thickness of the pile. The board rocks substantially the same amount each time, but the limits of this rocking movement are changed as the thickness of the pile decreases.

30 The lever 28 is loosely mounted upon a rock-shaft 29 extending between the side-frames and has a horizontal extension 61 (Fig. 2). On the end of this extension 61 is pivotally mounted a member 56 carrying 35 a pawl 58 and a roller 59, which latter is adapted to engage an abutment 60 projecting laterally from the adjacent side-frame 2. The arm 32 which rocks the feedboard is secured to the rock-shaft 29 and an arm 51 is also secured to this rock-shaft. This arm 40 51 carries a curved rack 52 at its end whose teeth are engaged by the pawl 58. A spring 57 connected to member 56 and lever 61 draws the pawl 58 toward the teeth of rack 45 52. The arm 51 has an extension projecting downwardly to which a spring 53 is connected, the other end of the spring being connected to the frame of the machine. A handle 54 is provided on arm 51 by which 50 the arm 51, arm 32 and feedboard 23 may be depressed and a latch 55 coacts with this handle to hold it in the depressed position.

When the low portion of cam 31 comes under roller 30, the levers 28, 61, 51 and 32 55 are rocked together until roller 59 engages the abutment 60 thus withdrawing pawl 58 from rack 52 and then spring 53 actuates lever 51, rock-shaft 29 and arm 32 to rock the feedboard until the top sheet of the pile 60 engages feeder 26. When lever 28 is again rocked by the cam, arm 61 is depressed until the pawl 58 is allowed to engage rack 52 and is then depressed a little farther so as to carry with it arm 51 and thus rock the 65 feedboard. It will thus be seen that the

feedboard, arm 32, and arm 51 carrying rack 52 are rocked but a small amount in each operation of arm 28, this amount being just enough to separate the pile from the feeder. As the pile of sheets on the feedboard decreases in height, the pawl 58 engages lower down upon the rack 52 so that the movement of the feedboard is the same or substantially the same in all cases. 70

Having described my invention, what I 75 claim as new therein and desire to secure by Letters Patent of the United States is:

1. The combination of a drum, a pivoted paper-support, a rotatable feeder overlying the same, means for rotating the drum and 80 feeder and for simultaneously rocking the paper-support once during each revolution of the drum, and adjusting devices for effecting an adjustment of the length of the 85 periods of oscillation of the paper-support relative to the rotation of the drum, substantially as set forth.

2. The combination of a drum, a rocking paper-support, a rotatable feed-roller with the under surface of which the paper on 90 said support is adapted to contact, means for rotating the drum and simultaneously rocking the support once during each revolution of the drum, and means for effecting an adjustment of the time of the rocking 95 movements of the support relative to the rotation of the drum to vary the duration of the time of contact of the paper on the support with the feed-roller, substantially as set forth. 100

3. The combination of a drum, a pressure-roller, a rocking feed-board, a feeder overlying one end of the feed-board, sheet-forwarding devices receiving sheets from the feeder and forwarding them to the drum and 105 pressure-roller, means for simultaneously rotating the drum and feeder, operating the sheet-forwarding devices and rocking the feed-board once during each revolution of the drum, and adjusting devices for effecting 110 an adjustment of said means for varying the time of the rocking movements of the feed-board relative to the rotation of the drum, substantially as set forth.

4. The combination of a drum, a pressure-roller, a feed-board, a feeder overlying the feed-board, means for rotating the drum and feeder and for simultaneously rocking the feed-board once during each revolution 120 of the drum to carry the paper on the feed-board into contact with the under side of the feeder, and means for effecting a variation of the duration of the time of contact of said paper with the feeder relative to the rotation of the drum, substantially as set forth. 125

5. The combination of a drum, a pressure-roller, a rocking feed-board, a feeder overlying one end of the feed-board, sheet-forwarding devices receiving sheets from the feeder and forwarding them to the drum 130

- and pressure-roller, means for simultaneously rotating the drum and feeder, operating the sheet-forwarding devices and rocking the feed-board once during each revolution of the drum, and means for effecting a variation of the time of contact of the paper on the feed-board with the feeder relative to the rotation of the drum, substantially as set forth.
- 10 6. The combination of a drum, a pressure-roller, a rocking feedboard, a rotatable feeder overlying one end of the feedboard, a rotatable sheet-forwarding device receiving sheets from the feeder and forwarding them 15 to the drum and pressure-roller, means for simultaneously rotating the drum and feeder, for rotating the sheet-forwarding device at the same surface speed as that of the drum and for rocking the feedboard once 20 during each revolution of the drum, and adjusting devices for effecting an adjustment of said means to vary the time of the rocking movements of the feedboard relative to the rotation of the drum, substantially as 25 set forth.
7. The combination of a drum, a pressure-roller, a pivoted feed-board, a feed-roller rotatable on its axis and overlying one end of the feed-board, means for rotating the 30 drum and feeder, a spring connected to the feed-board for turning the latter to carry the paper thereon into contact with the feeder, a two-part cam rotated by said means, means for effecting a relative adjustment of the parts of the cam and means for 35 causing the cam to rock the feed-board
- against the tension of said spring, substantially as set forth.
8. The combination of a drum, a pressure-roller, a feeder, a rocking feed-board having one end underlying the feeder, means for rotating the drum and feeder and simultaneously rocking the feed-board once during each revolution of the drum, adjusting devices for regulating the time of the rocking movements of the feed-board relative to the rotation of the drum, a stop overlying the end of the feed-board adjacent to the feeder and means for moving the stop into contact with the paper on the feed-board when the latter is in contact with the feeder and out of contact with said paper when the latter is out of contact with the feeder, substantially as set forth.
9. The combination of a rotary printing member, a feeder, a pivoted feedboard having one end underlying the feeder, a cam rotated once during each rotation of the drum, a lever rocked by the cam, a rock-shaft on which the lever is loosely mounted, a crank on said shaft connected to the feedboard, an arm on said shaft, a rack carried by this arm, a pawl pivotally mounted on said lever, a spring connecting the pawl and lever, and a stationary abutment coacting with said pawl, substantially as set forth.

This specification signed and witnessed this 29th day of January, 1913.
